UNITED STATES PATENT OFFICE.

JOSEPH CLEMENT GIGUÈRE, OF MONTREAL, QUEBEC, CANADA.

VENTILATOR.

Application filed August 18, 1927, Serial No. 213,917, and in Canada January 5, 1927.

The present invention pertains to a novel ventilator designed for application to a habitable structure for removing foul or vitiating air therefrom.

The principal object of the invention is the provision of a device of this character in which the atmospheric wind, regardless of its direction, aids in removing the foul air. In the accomplishment of this object the device is built essentially of a number of hollow air columns arranged circularly upon a base and spaced from each other to form intermediate wind channels lying radially with respect to the circular series of columns. The inwardly disposed walls of the columns are formed with vents establishing communication with the adjacent channels, and the base plate is formed with openings through which the interior of the columns may be brought into communication with a chimney or flue. Due to this construction, at least one of the channels will admit air from any direction and enable it to pass through the ventilator, thereby creating through the vents an aspiratory effect in the air columns, as a result of which the foul air is drawn out of the chimney or pipe on which the ventilator is mounted.

The invention is fully disclosed in the following description and in the accompanying drawings in which:

Figure 1 is a perspective view of the device;

Figure 2 is a detail vertical section on the line 2—2 of Figure 3;

Figure 3 is a detail horizontal section on the line 3—3 of Figure 2;

Figure 4 is a fragmentary bottom plan view; and

Figure 5 is a vertical diametrical section.

Reference to these views will now be made by use of like characters which are employed to designate corresponding parts throughout.

The device is constructed upon a slightly conical base 1 mounted upon a short pipe 2 adapted to fit over or within the chimney to which the ventilator is to be applied. The base is cut or stamped in such a manner as to form a series of pointed portions 3 around its periphery.

Upon the base are built several air shafts or columns each consisting of two angle plates 4 and 5. The member 4 is outermost and is provided at its edges with flanges 6

between which the free edges of the inner member 5 are received. The members 4 and 5 are retained at the lower edge by lugs 7 which may be stamped out of the base plate 1. Each air shaft or column, as clearly shown in Figures 1 and 3, is constructed in such a manner that the sides of the outer member 4 are parallel to the edges of the point 3 on which it rests, while the inner member 5 completes a diamond shaped figure pointing inwardly towards the centre of the base.

The several air shafts are, however, spaced from one another in substantially a circular series around the base so that between each pair of adjacent plates there remains a channel 8 disposed radially with respect to the base. From both sides of each inner member 5, namely the sides which border on the channels, longitudinal or vertical fins 9 are stamped inwardly of the air columns. Thus, vents 10 are provided for establishing communication between the interior of each air column and the adjacent channels 8. The lower end 11 of each vent is spaced to some extent from the base plate 1 in order to prevent the admission of snow which may accumulate on the base. These lower ends are further closed by appropriately shaped plates 12 which are secured in position in any desired manner.

Beneath each air shaft the base plate is formed with a sectoral opening 13 having its arc 14 disposed just within the circle defined by the pipe 2. It will be seen by a comparison of Figures 3 and 4 that radial arms or spokes 15 are retained beneath the openings 13 and that these spokes, which are integral parts of the base 1, constitute the bases of the channels 8.

The upper edges 16 of the outer plates 4 slope downwardly from the centre and are covered by a correspondingly conical top plate 17 formed with peripheral star points 18 resting directly upon the edges 16. Over the plate 17 is mounted a conical hood 19 held at a distance from the top plate by means of spacers 20. The plate 17 is formed with apertures 21 communicating with the space 22 between the members 17 and 19 and substantially in vertical alinement with the vertices of the sectoral openings 13.

The assembly is completed by a tie rod 23 passed from the centre of the dome 19 through a conical washer 24 mounted be-

neath the apex of the base 1 and retained in this position by a nut 25 threaded on the lower end of the rod.

In the operation of the device the wind, 5 whatever its direction may be, enters at least one of the channels 8 and escapes through one or more of the remaining channels at the other side of a diametrical vertical plane perpendicular to the wind direction. This travel of air through the ventilator has an aspiratory effect at the vents 10. Since the interior of the air columns is in communication with the chimney through the openings 13, this aspiratory effect 15 acts on the top of the chimney and establishes an upward draft therethrough. Further, the air passing between the upper plates 17 and 19 creates suction through the ports 21 and increases the suction effect 20 within the air columns.

While a specific embodiment of the invention has been illustrated and described, it is to be understood that various alterations in the details of construction may be made 25 without departing from the spirit of the invention as indicated by the appended claims.

Having thus fully described the invention, what I claim as new and desire to protect by Letters Patent is:

1. A ventilator comprising a base, a plurality of hollow air columns mounted vertically thereon in spaced relation, the walls of said columns being formed with vents 35 communicating with the spaces between the columns, a cover plate closing the upper ends of said columns, said cover plate having ports formed therein and disposed between the columns.

40 2. A ventilator comprising a base, a plurality of hollow air columns mounted vertically thereon in spaced relation, the walls of said columns being formed with vents communicating with the spaces between the 45 columns, a cover plate closing the upper ends of said columns, said cover plate having ports formed therein and disposed between the columns, and a hood mounted spacedly upon said cover plate.

50 3. A ventilator comprising a base, a plurality of hollow air columns mounted vertically thereon in spaced relation, the walls of said columns being formed with vents

communicating with the spaces between the columns, a cover plate closing the upper 55 ends of said columns, said cover plate having ports formed therein and disposed between the columns, a hood mounted spacedly upon said cover plate, and a tie rod passed from the centre of said hood through the 60 centre of said base.

4. A ventilator comprising a base, a plurality of hollow air columns mounted vertically thereon in spaced relation, the walls of said columns being formed with vents 65 communicating with the spaces between the columns, said base being formed with openings communicating with said columns, means for placing said openings in communication with a chimney, a cover plate 70 closing the upper ends of said columns, said cover plate having ports formed therein and disposed between the columns.

5. A ventilator comprising a base, a plurality of hollow air columns mounted vertically thereon in spaced relation, the walls of said columns being formed with vents 75 communicating with the spaces between the columns, said base being formed with openings communicating with said columns, 80 means for placing said openings in communication with a chimney, a cover plate closing the upper ends of said columns, said cover plate having ports formed therein and disposed between the columns, and a 85 hood mounted spacedly upon said cover plate.

6. A ventilator comprising a base inclined 90 downwardly from the centre, a plurality of hollow air columns mounted vertically thereon in spaced relation, the walls of said columns being formed with vertical vents 95 communicating with the spaces between the columns and extending a substantial distance from near the top and bottom of said ventilator, said base being formed with openings communicating with said columns, means for placing said openings in communication with a chimney, a cover plate 100 having ports formed therein and disposed between the columns, and a hood mounted spacedly upon said cover plates.

In witness whereof I have hereunto set my hand.

JOSEPH CLEMENT GIGUÈRE.
